Primary Examiner — Calvin E Vansant*Assistant Examiner* — Eidol Ghigliotti Torres(74) *Attorney, Agent, or Firm* — Kirk A. Buhler; Buhler & Associates(57) **CLAIM**

The ornamental design for an arbor press adapter, as shown and described.

DESCRIPTION

FIG. 1 is a top perspective view for an arbor press adapter showing my new design in an environment of use;

FIG. 2 is a front elevation view thereof;

FIG. 3 is a rear elevation view thereof;

FIG. 4 is a left side elevation view thereof;

FIG. 5 is a right-side elevation view thereof;

FIG. 6 is a top plan view thereof;

FIG. 7 is a bottom view thereof;

FIG. 8 is a right-side sectional view taken along lines 8-8 from FIG. 2 thereof; and,

FIG. 9 is a rear perspective view.

The broken lines in FIG. 1 depict environmental subject matter and form no part of the claimed design.

The arbor press adapter is shown with a symbolic break in its length. The appearance of any portion of the article between the break lines forms no part of the claimed design.
